(57) **CLAIM**

The ornamental design for a seat accessory, as shown and described.

DESCRIPTION

FIG. 1 is a front perspective view of the seat accessory showing a first embodiment of our new ornamental design in the environment of a sample vehicle seat;

FIG. 2 is a front view thereof;

FIG. 3 is a rear view thereof;

FIG. 4 is a top view thereof;

FIG. 5 is a left side view thereof;

FIG. 6 is a right side view thereof;

FIG. 7 is a front perspective view of the seat accessory showing a second embodiment of our new ornamental design in isolation;

FIG. 8 is a front view thereof;

FIG. 9 is a rear view thereof;

FIG. 10 is a top view thereof;

FIG. 11 is a bottom view thereof;

FIG. 12 is a left side view thereof; and,

FIG. 13 is a right side view thereof.

The broken lines shown in the drawings are for the purpose of illustrating environmental subject matter and form no part of the claimed design.

1 Claim, 10 Drawing Sheets
